UNITED STATES PATENT OFFICE.

WILLIAM D. LABADIE, OF SOUTH BEND, INDIANA, ASSIGNOR TO
WILLIAM MAURER AND DAVID J. McILREE, OF SOUTH BEND,
INDIANA.

ROTARY CLEANER.

SPECIFICATION forming part of Letters Patent No. 790,371, dated May 23, 1905.

Application filed October 24, 1902. Serial No. 128,558.

To all whom it may concern:

Be it known that I, WILLIAM D. LABADIE, a citizen of the United States, residing at South Bend, in the county of St. Joseph and State 5 of Indiana, have invented certain new and useful Improvements in Rotary Cleaners; and I do hereby declare the following to be a full, clear, and exact description of the invention, such as will enable others skilled in the art to 10 which it appertains to make and use the same.

My invention relates to a rotary cleaner for scraping or scouring the surfaces of nuts, caps, hand-hole plates, and boiler-heads of steam-boilers to remove the incrustation or 15 rust therefrom.

Most all water-tube boilers have a hand-hole formed in the header opposite each tube, such hand-hole being closed by a nut or cap which is removed when the flues are cleaned, 20 and the present invention is designed to remove the corrosion from the flanges and other surface of the caps in order that the parts may form steam-tight joints when fitted together; and to these ends the invention consists in the 25 construction and combination of parts, all as will be more fully described hereinafter and illustrated in the accompanying drawings, in which—

Figure 1 is a longitudinal vertical section 30 on a line $\alpha\alpha$ of Fig. 2, showing the device applied to the hand-hole plate of a boiler. Fig. 2 is an end view of the device, showing the disk with the scraping-blades thereon. Fig. 3 is a detail view in section, showing one 35 of the scraping-blades fitted in its socket. Fig. 4 is a section of sleeve and spindle on a line yy of Fig. 1.

Referring to the drawings in detail, 1 designates a rotary spindle journaled in a suitable head 4. The rotary spindle is provided 40 at one end with a handle 2, and upon the other end of the spindle is mounted for rotation with the same a scraping member comprising a disk 3, carrying scraping-blades 10, herein- 45 after described. The head 4 consists of a disk-shaped block having raceways on each face, which align with raceways formed in the

disk 3, and a flanged collar 5, and in which there are fitted balls 6 and 7 to form a thrust ball-bearing for the disk and spindle. Se- 50 cured to the block and extending from one side thereof is a cylindrical extension 8, which surrounds the spindle and provides a convenient hand-grasp when the machine is in use. By mounting the head on the spindle between 55 the flanged collar 5 and the disk 3 a thrust ball-bearing is provided for the spindle. On the inner face of the disk 3 there is formed an annular flange 9, which incloses the periphery of the head 4 and serves as a guard to prevent the scrapings or other impediments working between the head and disk. At the outer edge of the disk 3 are formed sockets 11 for the reception of the scraping-blades 10, provided with slots a at their inner ends. The blades 60 10 are adjustably secured in the sockets 11 by clamping-screws b , which pass through the slots a of the blades and have a threaded engagement with one of the side walls of each of the sockets, the heads of the clamping-screws b lying in 65 apertures c , formed in the opposite side walls of the sockets and frictionally engaging the blades. A scouring device consisting of a smaller disk 12, faced with emery-paper, is also mounted on the spindle to rotate therewith and 70 is employed for scouring the faces of small nuts or caps of boilers. The disk 12 forms a backing for the emery-paper, which may be secured by a nut 13 or similar device. The spindle is revolved by means of a sleeve 14, 75 adapted to engage the spiral grooves 16, formed in the spindle, so that when the sleeve is reciprocated longitudinally on the spindle the latter will be rotated in the head 4, and the cap or hand-hole plate, which is held in a 80 vise, will be acted on by the scraping-blades and the emery-paper to remove the incrustation or rust which has accumulated thereon. Springs 17 are secured to the head by a 85 jam-nut 18 in order to give movement to cutting-knives before contacting with the face of nut, cap, or hand-hole to be cleaned, the pressure of operator on the knob 2 revolving the disk 3 and overcoming the tension of 90

springs 17, thus bringing knives 10 in contact with surface to be cleaned or scraped while revolving.

What I claim, and desire to secure by Letters Patent, is—

1. In a device of the character described, the combination with a relatively fixed head, a scouring member rotatably mounted upon the front of the head, means carried by the head for rotating the scouring member, and bowed springs carried by the head and projected across the periphery of the scouring member and at the front thereof to form an initial yieldable support for the head.
2. In a device of the character described, the combination with a relatively fixed head having concentric raceways in the back and front thereof, of a tubular hand-grasp carried by the head and inclosing the raceway in the back thereof, a rotatable spindle extending through the hand-grasp and piercing the head, said spindle having its rear end por-

tion provided with a spiral and also provided with an external annular shoulder within the hand-grasp and provided with a raceway corresponding to the raceway in the back of the head, antifriction devices in said raceways, a scraping member carried by the forward end of the spindle and provided with a raceway corresponding to the raceway in the front of the head, antifriction devices in said raceways, bowed springs carried by the head and projected across the periphery of the scraping member and in front thereof, and a reciprocating operating-sleeve embracing the spiral portion of the spindle and having a part engaging the same to rotate said spindle and scraping member.

In testimony whereof I affix my signature in presence of two witnesses.

WILLIAM D. LABADIE.
